UNITED STATES PATENT OFFICE

160,706

ILLUMINATING SCREWDRIVER

Carl R. Hettrick, Terrace Park, Ohio

Application October 29, 1949, Serial No. 5,779

Term of patent 14 years

(Cl. D93—4)

To all whom it may concern:

Be it known that I, Carl R. Hettrick, a citizen of the United States, and a resident of Terrace Park, in the county of Hamilton, and the State of Ohio, have invented a new, original, and ornamental Design for an Illuminating Screwdriver, of which the following is a specification, reference being made to the accompanying drawing, forming a part hereof.

Fig. 1 is a side view of an illuminating screwdriver, showing my new design.

Fig. 2 is a side view taken 90° from the view shown in Fig. 1.

Fig. 3 is an end view of the screwdriver.

I claim:

The ornamental design for an illuminating screwdriver, as shown.

CARL R. HETTRICK.
